UNITED STATES PATENT OFFICE.

SOLOMON ANDRADE LAZARUS, OF LONDON, ENGLAND.

TOOTHBRAH.

Application filed June 4, 1924, Serial No. 717,789, and in Great Britain June 21, 1923.

My invention relates to improvements in tooth-brushes.

According to the invention I make the bristle member of a tooth, nail or like brush detachable with respect to the handle, on which it is so mounted that it can revolve thereon in such a manner that, as it is used, a fresh bristle surface is continuously presented to the teeth or other object being cleaned.

In a suitable construction of brush embodying the invention, the bristles are advantageously secured spirally around an axial wire or other support, the ends of which can be sprung or by other suitable means brought into engagement with holes or recesses in a pair of projections or lugs on the brush back, the said holes or recesses forming bearings in which the cylindrical bristle member can revolve.

As will be understood, the spiral arrangement of the bristle tufts tends to cause the bristle member, when rubbed against the teeth or the like, to rotate on the handle and so to bring a fresh surface continually into use.

To enable the invention to be fully understood I will describe it by reference to the accompanying drawing, in which:

Figure 1 is a side view of a tooth-brush constructed in accordance with my invention.

Figure 2 is a view at right-angles to Figure 1.

Figure 3 is a section on the line 3—3, Figure 1.

Figure 4 is a cross section of the bristle member of the brush but drawn to a larger scale than the preceding figures.

Figure 5 is a side view of a modified form of my improved brush and

Figure 6 is a section on the line 6—6, Figure 5.

Figure 7 is a side view of another modification of the brush and

Figure 8 is a section on the line 8—8, Figure 7.

a is the handle of the brush, *b* the back thereof and *c* the cylindrical bristle member of the said brush, the said bristle member comprising a series of bristles *d* arranged spirally around the axial support or shaft *e*, which, in the drawing, is formed of a pair of wires twisted spirally and between which the bristles are inserted and from the opposite sides of which they pro-

ject in the form of a double threaded screw. *f*, *f* indicate the pair of projections or lugs on the back *b* having the holes or recesses *g* in their opposed faces to form the bearings for the reception of the ends of the shaft *e*, which ends are advantageously tapered, as shown, and the said holes or bearings correspondingly tapered.

By the described construction it will be understood that when in use, the bristle member *c*, owing to the spiral arrangement of the bristles, will, when rubbed against the teeth, slightly rotate so as to bring a fresh surface of bristles continually into use.

In the form of the invention illustrated in Figures 1 to 3, the projections or lugs *f* are formed integral with the back *b*, whilst in the form illustrated in Figures 5 and 6, the said lugs are formed separately from the said back and cemented or otherwise secured thereto. In the form of the invention illustrated in Figures 7 and 8, the projections or lugs are integral with a wire *h* which engages in a groove or recess in the back *b* and is cemented or otherwise fixed therein.

In all the forms of the invention illustrated, the bristle member *c* is designed to be sprung into or out of engagement with the bearings *g*, a notch *i* in the face of one of each pair of projections or lugs *f* facilitating such operation. For instance, when engaging the said bristle member with the brush back, one end of the shaft *e* is first engaged with the bearing in the lug *f* opposite to the one provided with the notch *i* and then the other end of the said shaft is moved into engagement with the said notch and then forced down into the bearing into which the notch leads.

A tooth-brush made according to the invention, possesses a number of advantages, in practice. For example, it is more sanitary than brushes as heretofore made since the bristles are more easily accessible for cleaning and can even be entirely removed from the back for that purpose. Again, since the bristles are rotatable on the back or holder a fresh surface is constantly being presented to the teeth. This prolongs the life of the brush. Furthermore, the bristles can be reversed in position in the brush this, again, prolonging its life and when a bristle member is worn, it can easily be renewed.

Although the invention has been described

as applied to tooth-brushes, it is to be understood that it is equally applicable to nail and other brushes.

Having now particularly described and ascertained the nature of my said invention and in what manner the same is to be performed, I declare that what I claim is:—

A tooth brush consisting of a handle provided at one end with a pair of spaced lugs 10 formed with aligned and opposed bearing

recesses, and a detachable bristle member, revoluble with free rotary motion with respect to said handle; said member comprising a straight axial shaft having bristles secured spirally therearound, and adapted to 15 be revolved by the brushing action, said shaft being of a resilient nature, whereby it can be sprung into and out of engagement with said bearing recesses.

SOLOMON ANDRADE LAZARUS.
